DOUBLE BEARING RAIL ANTICREEPER

Frederick A. Preston, Lake Forest, Ill., assignor to
 Poor & Company, Chicago, Ill., a corporation of
 Delaware

Application June 16, 1938, Serial No. 213,970

14 Claims. (Cl. 238—327)

This invention relates to rail anti-creeper devices adapted to clampingly grip a rail and bear against a side face of a cross-tie, and more specifically to devices of this type comprising a bar 5 bent to provide jaws adapted to be forced into spring clamping engagement with the base portion of a rail and having a body portion which extends substantially horizontally beneath the rail so as to press against the side face of a cross-tie and thereby prevent lengthwise movement 10 of the rail.

Rail anti-creepers of the above type maintain their position on the rail by virtue of the resilient clamping action of the jaws, but the resilient grip is supplemented, during the presence of creeping pressure on the rail, by a canting or lever grip of the jaws on the rail, the said grip resulting from the pressure of the under-rail portion of the device against a side face of a 20 cross tie tending to cant the jaws. While the said canting grip of the jaws is important, it is equally important to obtain such grip without any actual canting or spreading of the jaws. In order to obtain the above character of grip, 25 it has been customary heretofore to form said anti-creepers from metal bars of rectangular cross-section having the desired horizontal width to produce a strong lever gripping action when the device is pressed against a cross-tie and being relatively thick vertically to resist spreading 30 of the jaws during such lever-gripping action.

When the under-rail portion of the above type of anti-creeper extends horizontally beneath the rail, the tie bearing area is limited to the vertical 35 thickness of the bar stock. Such devices, therefore, are not entirely satisfactory for use in situations where tie plates are interposed between the rail and the usual wooden cross-ties. In such situations, the rail and the anti-creeper 40 device applied thereto are elevated relative to the top of the tie. This condition reduces the tie bearing area of the anti-creeper body and consequently increases the likelihood of the device cutting into and thereby damaging the wooden 45 cross-tie.

Anti-creeper devices of the above general character, when made of relatively thick bar stock, present a further disadvantage in that the portions of the anchors which overlie the 50 top surface of the rail, do not yield readily when they are struck by a derailed car wheel or by dragging rigging. These and similar impacts against the anchor jaws frequently result in 55 forcing the jaws of the anti-creepers through

the rail base flange or otherwise distort and damage the rail base.

A principal object of the present invention is to provide an improved rail anti-creeper which is particularly suitable for use in situations in 5 in which a tie plate is interposed between the rail and the top surface of an ordinary wooden cross-tie. In this connection, the invention includes the provision of two vertical surfaces 10 adapted to bear against the rail supporting structure, that is to say, one surface for bearing against the wooden cross-tie and another surface for bearing against the edge portion of a tie plate supported on the tie and thereby utilize 15 substantially the entire side face of the anti-creeper device as an abutment surface.

Another object is to provide an improved anti-creeper device of the above character having sufficient width whereby either side face of the device can be positioned to bear against the side 20 face of a cross tie and abut against the edge of a tie plate spaced from the said side face of the tie and to provide in such device rail gripping surfaces having widths which are substantially less than the over-all width of the bar 25 from which the anchor is formed, whereby a relatively wide anchor device may be provided with rail gripping surfaces of suitable width for effecting a maximum shackle grip on the rail base when the under-rail portion of the anti-creeper is pressed against the cross-tie against 30 the tie plate.

A further object is to provide an anti-creeper construction in which the portion overlying the base flange of the rail may be made of suitable 35 vertical thickness to provide the desired strength for preventing creeping movement of the rail, but which will function to relieve the base flange of the rail from the shearing and distorting strains when the anchor is struck by a derailed 40 wheel and/or other parts of a car.

According to the present invention, the body portion of the anti-creeper is formed with a lateral projection which extends into the space between the rail and the cross-tie underlying the rail so as to abut against a tie plate mounted on the cross-tie. The width of the said projection is such that when it is in abutting engagement with the tie plate, the lower portion of the anti-creeper body will bear against the side face of the cross-tie. By off-setting the side face of the anti-creeper body in the above manner, substantially 45 the entire area of the side face is utilized as an abutment surface and consequently 50 55

resists any tendency of the anti-creeper body to cut into the wooden cross-tie.

The cross-sectional configuration of the device may be such that either side of the device can be arranged to bear against the cross-tie and to overlie the top face thereof so as to abut against a tie plate. Such construction involves making the anchor somewhat wider than is desirable for producing an efficient lever or canting grip on the rail. The invention, therefore, contemplates making the rail gripping surfaces of the device somewhat narrower than the width of the bar stock. The cross-section of the bar also provides an upper jaw which is relatively thick vertically of the rail so as to provide the desired rail gripping qualities but which will bend under a severe impact and/or deflect the members striking the same so as to prevent notching or other damage to the rail base.

Other objects and advantages of the invention will be readily apparent from the detailed description of the embodiments shown in the accompanying drawings, wherein

Fig. 1 is a side view of a rail anti-creeper device constructed in accordance with the principles of this invention and applied to the base portion of a rail.

Fig. 2 is an end view of the anti-creeper structure, cross-tie and tie plate illustrated in Fig. 1.

Fig. 3 is a vertical section taken on line 3—3 of Fig. 1 illustrating the cross-sectional configuration of the anti-creeper jaws and showing also the manner in which the under rail portion of the anti-creeper bears against the cross-tie and the tie plate.

Figs. 4 and 5 are views similar to Figs. 1 and 2, but illustrate a modified construction of anti-creeper device.

Fig. 6 is a vertical section taken on line 6—6 of Fig. 4, and

Fig. 7 is a side view of another modified embodiment.

Referring first to Figs. 1, 2 and 3 of the drawings: the base portion 10 of a railroad rail is supported on a tie plate 11. The tie plate may be secured to the top face of a wooden cross-tie 12 by means of any suitable attaching devices, for example, the cut spikes 13 which are driven through openings 14 of the tie plate and into the cross-tie.

The said improved rail anti-creeper shown in the drawings is made from a bar of substantially T-shape in cross-section. One end of the bar is bent into hook form to provide upper and lower jaws 15 and 16 which grip the top and bottom surfaces of the rail base at one side of the rail with resilient pressure. Preferably the hook end is formed to provide an abutment surface 17 for engaging the edge 18 of the rail base to limit the applying movement of the device. The said abutment surface preferably, though not necessarily, extends vertically, as shown in Fig. 1. The said jaw end of the device is also formed to provide clearance spaces 19 and 20 above and below the said flange, respectively. The body portion 21 of the device extends horizontally across beneath the rail base and is formed with a shoulder 22 which engages the lower corner portion of the rail base at the other side of the rail to lock the anchor in its applied position. The shoulder 22 is held in its locking position by the resilient pressure exerted by the jaw 15 on the top surface of the rail base. The lateral arms 23—23a of the T-shaped body are of such width and thickness that either of the arms is adapted to extend into

the space between the rail base 10 and the top of the cross-tie 12 so as to bear against the edge portion 24 of the tie plate 11. The said arms 23—23a are preferably of different widths so as to insure engagement with the said edge portion 24 of the tie plate when the said edge is spaced inwardly from the side of the tie plate at different distances or when the said tie plate may be of different width relative to the width of the cross-tie. When a lateral arm 23 or 23a of the anti-creeper body is in engagement with the tie plate, a vertical web 25 of the T-shaped body bears against the side face of the cross tie 12. The pressure incident to the longitudinal movement of the rail is, therefore, distributed between the side face of the wooden cross tie and the edge surface 24 of the tie plate. The said pressure which is transmitted to the tie plate is in turn transmitted to the underlying cross-tie through the spikes 13 or such other tie plate fastening means as may be employed. In order to provide the device with rail gripping surfaces of suitable width for exerting an efficient lever grip on the rail base, for example, at the points A and B, when the lower portion of the anti-creeper device is pressed against the cross-tie, the rail gripping faces of the device are formed of less width than the width of the bar. This is accomplished, preferably, by recessing the upper faces of the cross arms 23—23a, as indicated at C and D in the drawings, and thereby confine the effective width E of said rail gripping surfaces of the upper and lower jaws 15 and 16 to any desired dimension. In some situations it is desirable to also reduce the frictional area of the rail gripping portion of the anchor. This result is accomplished by recessing the rail gripping portions of the device, as indicated at F. The said web 25 serves both as a tie abutting member and a rigidifying means for the hook shaped end of the anti-creeper and may be made of any suitable height to provide a desired tie bearing effect and to provide the desired strength at the hook end of the device to prevent spreading of the rail gripping jaws thereof during the lever gripping action of the device when the body portion is pressed against the cross tie and the tie plate.

The thickness of the vertical web portion 25 is preferably such that, when the device is moderately tempered, as contemplated, the said web will be readily crushed or bent in the event that it is struck by a derailed car wheel or by dragging rigging of the car. The bending and crushing of the said web, together with the downward bending of the upper jaw at the clearance space 19 serves to cushion the impact of a derailed wheel thereon and thereby prevent such impact from punching the anti-creeper jaw through the base flange of the rail.

The anti-creeper device may be applied to its operative position on the rail by loosely fitting the hook end of the device over one flange of a rail base in a position whereby one or the other of the said arms 23—23a will project into the space between the rail and the cross tie so as to engage the surface 24 of the tie plate and whereby the web 25 of the body will bear throughout the length of the body against the side face of the cross tie. The upper and lower jaws may be forced into desired gripping engagement with the rail base by driving the device bodily transversely of the rail until the locking shoulder 22 snaps up over the edge of the rail base. When the anchor is applied in this manner the resilient gripping pressure of the hook end maintains the

anchor on the rail and also aids in resisting lengthwise movement of the rail. The said resilient pressure is supplemented during the presence of creeping pressure on the rail by the lever gripping action exerted at points A and B when the under rail portion of the anti-creeper device is pressed against the side face of the adjacent cross-tie.

The anti-creeper device shown in Figs. 4, 5 and 6 of the drawings is of the same type as shown in Figs. 1, 2 and 3, but is made from a bar of different cross section. The cross-sectional shape of the bar may be briefly described as comprising flat faces 27 and 28 which extend substantially perpendicular to each other, a curved outer surface 29 which extends from one of said flat faces to the other, and a lateral flange 30 which projects outwardly from the plane of the flat face 28 and has one side face extending in the plane of the face 27. The flange 30 is preferably offset relative to the surface so that the width of the said rail gripping surface will be less than the full width of the bar.

The said bar is bent at one end into hook form to provide upper and lower jaws designated 15a—16a and so that the face 27 of the bar will constitute the rail gripping surfaces of the anti-creeper device. The under-rail portion 21a of the anchor, like that of the corresponding portion of the previous embodiment, extends horizontally across beneath the base flange 10a and is provided with a locking shoulder 22a.

The modified device is applied to the rail base in the same manner as described in connection with the previous embodiment. When the anchor is in its applied position, the flange 30 extends into the space between the rail base 10a and the wooden cross tie 12a so as to bear against the vertical edge face 24a of the tie plate, and the vertical face 28 of the bar bears against the side face of the cross tie. The offset faces defined by the outer edge of the flange 30 and the vertical surface 28 give the anti-creeper device abutment surfaces corresponding substantially to the entire area of the one side face of the body portion of the device and will satisfactorily transmit the creeping pressures of the rail to the cross-tie and tie plate without danger of the body portion of the anti-creeper being pressed into the side face of the wooden cross-tie.

The outer face 29 of the upper jaw 15a, being curved preferably in the direction of the movement of the traffic, functions to deflect any dislocated part of a car rigging which may be dragging along the rail. The said face 29 of the upper jaw also reduces the effective height of the jaw at the side which would be most likely to receive the initial impact of a derailed car wheel. The said reduced height of the jaw, together with the deflecting action of the curved surface thereof and the downward flexing of the jaw at the space 19a serves to cushion and deflect such impact and thereby avoid notching or otherwise damaging the rail base flange.

The anti-creeper device shown in Fig. 7 is formed to grip the top and bottom surfaces of a rail base at one side only of the rail. It is preferably, made from a metal bar having the same cross-sectional configuration as illustrated in Figs. 1, 2 and 3, so that the under rail portion of the device will bear against the rail supporting structure and the vertical flange 25b will function in the same manner as described in connection with that embodiment. The upper and lower jaws 15b—16b of the present modification

grip the top and bottom surfaces of one base flange of the rail base 10b with sufficient force to maintain the device on the rail. The lower jaw 16b extends horizontally beneath the rail base a distance sufficient to provide a suitable rail gripping surface 16c. The said lower jaw, however, does not necessarily extend entirely across the rail base and does not engage opposite edges of the said base.

I claim:

1. A rail anti-creeper comprising a member provided with upper and lower jaws for gripping the base flange of a rail and having a body portion formed to extend beneath the rail base; the said body being formed with a portion for abutting engagement with the side face of an adjacent cross-tie and a portion for engagement with a tie plate supported on said cross-tie; and the said jaws being formed with rail gripping portions, the effective widths of which for exerting a lever grip on the top and bottom surfaces of the rail base are less than the width of the said body.

2. A rail anti-creeper comprising a member provided with upper and lower jaws for gripping the base flange of a rail and having a body portion formed to extend beneath the rail base; the said body being formed with a portion for abutting engagement with a side face of an adjacent cross-tie and a portion adapted to overlie the top face of the cross-tie and abut against a tie plate supported on said cross-tie and the said jaws and body portions being provided with rail gripping surfaces, the effective widths of which for exerting a canting grip on the rail base are less than the width of the anti-creeper.

3. A rail anti-creeper comprising a member provided with means for gripping the base flange of a rail and having a body portion formed to extend horizontally beneath the rail base; the said body being formed with a portion for abutting engagement with a side face of an adjacent cross-tie and a portion for engagement with a tie plate supported on said cross-tie and the said gripping means being formed with rail gripping surfaces having effective widths for exerting a lever grip on the rail base which are less than the width of the said body.

4. A rail anti-creeper comprising a member provided with means for gripping one base flange of a rail and having a body portion formed to extend horizontally beneath the rail base; the said body being formed with a portion for abutting engagement with a side face of an adjacent cross-tie and a portion adapted to overlie the top face of the cross-tie and abut against a tie plate supported on said cross-tie and the said bar having a recess along one marginal surface thereof to restrict the width of the rail gripping surfaces of the bar.

5. A rail anti-creeper comprising a member provided with means for gripping the base flange of a rail and having a body portion formed to extend beneath the rail base; the said body being formed on each side face with a portion for abutting engagement with a side face of an adjacent cross-tie and a portion adapted to overlie the top face of the cross-tie and abut against a tie plate supported thereon, whereby the pressure incident to longitudinal movement of the rail is distributed between the side face of the cross-tie and an edge portion of the tie plate; and the said rail gripping means having effective widths for exerting a lever grip on the rail which are less than the full width of the under-rail body portion of the bar.

6. A rail anti-creeper comprising a bar bent at one end into hook form to provide a jaw for gripping one base flange of a rail and having a substantially straight body portion for extending across beneath the rail base and provided at its end with means for locking engagement with the other base flange; a side face of said body being formed with vertical surfaces offset with relation to each other and having a combined vertical height greater than the effective width of the rail gripping surface of the bar extending the full length of said body, one of said surfaces being adapted to bear against a side face of a cross-tie and the other of said surfaces being adapted to abut against a vertical edge portion of a tie plate positioned on the cross-tie and spaced inwardly from the said side face thereof.
10. A rail anti-creeper comprising a bar bent at one end into hook form to provide a jaw for gripping one base flange of a rail and having a substantially straight body portion for extending across beneath the rail base and provided at its end with means for locking engagement with the other base flange; the side faces of said body being formed with vertical surfaces offset with relation to each other to provide horizontal flanges of different widths and extending the full length of the body, whereby either side of the body may be positioned to bear against a side face of a cross tie and against a tie plate supported thereon.
15. A rail anti-creeper comprising a metal bar substantially T-shaped in cross section and bent at one end into hook form to provide jaw portions for gripping the top and bottom surfaces of one base flange of the rail, a substantially straight body portion for extending across beneath the rail base, and means at the end of the body remote from the hook for engaging the other base flange to lock the device on the rail; the said bar being so proportioned and being bent so that the stem portion of its T-shaped cross-section provides a tie abutting face of greater height than the effective rail gripping width of the bar and whereby the laterally projecting arms of the T-bar are adapted to overlie the top surface of said cross-tie and abut against a tie plate interposed between the rail and said tie.
20. A rail anti-creeper comprising a metal bar substantially T-shaped in cross section and bent at one end into hook form to provide jaw portions for gripping the top and bottom surfaces of one base flange of the rail, a substantially straight body portion for extending across beneath the rail base, and means at the end of the body remote from the hook for engaging the other base flange to lock the device on the rail; the said bar being bent so that either side of the stem portion of its T-shaped cross section may be positioned to bear against a side face of a wooden cross-tie and whereby either of the laterally projecting arms of said T-bar are adapted to extend between the base portion of the rail and said cross-tie so as to abut against a tie plate positioned on the tie and the marginal portions of the said lateral arms being offset to reduce the width of the rail bearing surfaces relative to the width of the bar.
25. A rail anti-creeper comprising a metal bar bent at one end into hook form to provide a jaw adapted to overlie and grip the top surface of a rail base flange, a body portion for extending horizontally across beneath the rail and adapted to project over the top of a cross tie and abut against an edge portion of a tie plate interposed between the rail and the tie, a locking shoulder at the end of the body remote from the hook for engaging an edge of the rail base to lock the device on the rail, and a reinforcing rib of greater height than the effective rail gripping width of the bar extending lengthwise of said body and said jaw adapted to bear against the side face of said cross-tie, whereby the pressure incident to creeping movements of the rail are transmitted to the side face of the cross-tie and to the said tie plate.
30. A rail anti-creeper comprising a metal bar bent at one end into hook form to provide a jaw adapted to overlie and grip the top surface of a rail base flange, a body portion for extending horizontally across beneath the rail and adapted to project over the top of a cross tie and abut against an edge face of a tie plate interposed between the rail and the tie, a locking shoulder at the end of the body remote from the hook for engaging an edge of the rail base to lock the device on the rail, and a relatively thin reinforcing rib of greater height than the effective rail gripping width of the bar extending lengthwise of said body and said jaw adapted to bear against the side face of said cross-tie, whereby the pressures incident to creeping movements of the rail are transmitted to the side face of the cross tie and to the said tie plate and whereby a portion of the rib on the said jaw overlying the rail base and in the path of a derailed car wheel will bend and thereby cushion the impact of the wheel against said jaw for the purpose described.
35. A rail anti-creeper comprising a metal bar bent at one end into hook form to provide a jaw adapted to overlie and grip the top surface of a rail base flange, a body portion for extending horizontally across beneath the rail and adapted to project over the top of a cross-tie and abut against an edge face of a tie plate interposed between the rail and the tie, a locking shoulder at the end of the body remote from the hook for engaging an edge of the rail base to lock the device on the rail and a relatively wide but thin reinforcing rib extending lengthwise of said body and said jaw adapted to bear against the side face of said cross-tie, whereby the pressures incident to creeping movements of the rail are transmitted to the side face of the cross-tie and to the said tie plate and whereby the portion of the rib on the jaw overlying the rail base and in the path of a derailed car wheel will bend and thereby cushion the impact of the wheel against said jaw; the said jaw being formed also to provide substantial clearance above the marginal portion of the rail base flange, whereby downward bending of the jaw when struck by a derailed wheel supplements the cushioning effect of said rib.
40. A rail anti-creeper comprising a bar bent at one end into hook form to provide a jaw for gripping one base flange of a rail and having a substantially straight body portion for extending across beneath the rail base and formed at its end with means for locking engagement with the other base flange; one side face of said bar being formed with a lateral rib offset in relation to the rail gripping surfaces of the bar and providing a portion adapted to overlie the top surface of the cross tie and abut against a tie plate positioned on the tie, and another side of the bar being inclined to provide said jaw with a combined ramp and deflecting surface, there being clearance between the jaw and the upper

surface of the rail base flange whereby the ramp provides for movement of a derailed wheel over the jaw and the downward bending of the jaw serves to cushion the impact of the derailed 5 wheel.

14. A rail anti-creeper comprising a metal bar bent intermediate its ends to provide a jaw for gripping the top surface of a rail base flange and to provide a lower jaw which extends horizontally 10 beneath the rail for a portion of its width only;

the said lower jaw portion being formed with a portion for abutting engagement with a side face of an adjacent cross-tie and a portion adapted to overlie the top face of the cross-tie and bear against a tie plate supported on said cross-tie, 5 the said overlying portion of the bar being offset relative to the rail gripping face thereof, whereby the span of said gripping face is of less width than the bar.

FREDERICK A. PRESTON. 10
